LATCHING STRUCTURE

William L. Fox, Baltimore, Md., assignor to Polan,
Katz & Company, Baltimore, Md., a firm

Application December 7, 1933, Serial No. 701,387

4 Claims. (Cl. 135—46)

This invention relates to a latching structure designed primarily for use in connection with umbrellas for detachably connecting the handle and staff thereof together, but it is to be understood that a latching structure in accordance with this invention may be employed in any connection for which it may be found applicable, and the invention has for its object to provide, in a manner as hereinafter set forth, a latching structure 10 arranged relative to an umbrella handle and staff for expeditiously connecting and disconnecting them when occasion requires and when disconnected from each other permitting of the staff and cover of the umbrella being stored in a space of 15 less limited length than would be the case if the handle was permanently connected to the staff.

A further object of the invention is to provide, in a manner as hereinafter set forth, a latching structure for the purpose referred to which when 20 in latching position relative to an umbrella handle and staff will prevent the turning and arrest the pulling away from one relative to the other, as well as further preventing the accidental separation of the handle and staff.

25 Further objects of the invention are to provide, in a manner as hereinafter set forth, a latching structure for the purpose referred to, which is simple in its construction and arrangement, strong, durable, compact, thoroughly efficient in 30 its use, conveniently operated, readily installed with respect to the handle and staff of an umbrella, and inexpensive to manufacture.

To the above ends essentially, and to others which may hereinafter appear, the invention consists of such parts, and such combination of parts which fall within the scope of the invention as claimed.

In the drawing:

Figure 1 is a fragmentary view in elevation 40 and partly in section of an umbrella showing the adaptation therewith of the latching structure in latching position.

Figure 2 is a fragmentary view in vertical section of an umbrella handle and staff illustrating 45 the adaptation therewith of the latching structure in non-latched position.

Figure 3 is a perspective view of the latching element.

Figure 4 is a perspective view of the combined 50 guide and keeper element for the latching element.

Figure 5 is a fragmentary view in perspective of the combined guide and keeper element looking towards the bottom of the latter.

55 In the drawing, 1 generally indicates the staff

of an umbrella 2. The staff 1 comprises a wooden body 3 encased by a metallic tube 4 which is flanged at its inner end, as at 5. The body 3 extends beyond the flanged end of tube 4 and is formed with a lengthwise extending axially arranged cylindrical socket 6 opening at the inner end 7 thereof. The said inner end 7 is peripherally rabbeted, as at 8. Encompassing and seated against rabbet 8 is an axially apertured metallic cap member 9. The aperture in the latter is designated 10 and has its edge registering with the wall of socket 6. The cap member 9 reinforces the rabbeted inner end 7 of the body 3. The umbrella cover and ribs are designated 11, 12 respectively. The handle of the umbrella is indicated at 13 and includes a shank portion 14 which, when the staff 1 and handle 13 are latched together, overlaps the cap member 9. The shank portion 14 has an axially arranged lengthwise extending socket 15 opening at the free end 16 thereof. The wall of socket 15 is upon two different diameters and at the junction of said diameters a shoulder 17 is formed. That portion of the wall of socket 15 which is of largest diameter extends from shoulder 17 to the said end 16.

The latching structure includes a tubular latching element 18, a tubular combined guide and keeper element 19 for the latching element 18 and an expelling means 20 for element 18. The means 20 also functions to maintain the element 18 in latching engagement with respect to element 19.

The element 18 has spaced peripheral cavities 21 and a radially disposed latching pin or stud 22 intermediate its ends extending outwardly therefrom. The element 18 is of greater length than the socket 15 and has a portion of its length positioned in the latter. The element 18 projects beyond the free end 16 of the shank portion and is also encompassed by the wall portion 23 of the portion of largest diameter of socket 15.

The wall portion 23, shoulder 17 and element 18 provide a socket 24 for a purpose to be referred to. The pin or stud 22 is arranged in permanent spaced relation to and outwardly of the edge of the free end 16 of the shank portion 14. That part of the element 18 which is arranged in that portion of smallest diameter of the socket 15 is anchored to the shank portion 15 by a cementitious material 25 interposed between the wall portion 26 of socket 15 and element 18. The cementitious material also extends into the peripheral cavities 21 and assists in fixedly anchoring handle 13 and element 18 together.

The keeper element 19 is of greater length than socket 6 and has a portion thereof secured in the 110

socket 6 and its remaining portion projecting beyond the end 7 of body 3. The periphery of element 19 is formed with a series of annular spaced grooves 27 at its inner end portion. From a point 5 spaced from the outer end of element 19 to the outer groove 27, the periphery of element 19 is knurled as at 28. The periphery of element 19 from the outer end of the knurled portion to the outer end of said element, as indicated at 29, is 10 plane. The periphery of element 19 between grooves 27 and below the inner groove 27 is knurled as at 30. The element 19 in that portion thereof having a plane outer periphery is formed with a slot 31 disposed lengthwise thereof. The slot 31 includes a spiral stretch 32 opening at one end at the edge 33 of element 19. The slot 31 also includes an L-shaped stretch formed of a horizontal leg 34 and a leg 35 disposed lengthwise of element 19. The stretch 32 has its 15 outer end merge into one end of the leg 34. The leg 35 is disposed at right angles to leg 34 and extends in a direction to oppose a part of stretch 32, the latter being of greater length than that of legs 34, 35. The other end of leg 34 merges 20 into the open end of leg 35. The stretch 32 provides for the rotating of element 18 when the latter is being latched to element 19 and which 25 will be presently referred to.

The expelling means 20 includes an abutment 36 in the form of a plug, preferably of cork, anchored within that end of element 19 within the socket 6. Abutment 36 is secured to element 19 by a diametrically disposed pin 37 extending through the abutment and anchored to element 30 19. The means 20 also includes a coiled compression spring 37 seated on abutment 36 and arranged in the path of the outer end of element 18. The outer diameter of the latter with respect to the inner diameter of element 19 is such as to permit of element 18 freely moving in element 19 during the latching and unlatching operation.

That part of element 19 within the socket 5 is anchored to body 2 by cementitious material 38 which is interposed between the knurled peripheral portions of element 19 and the wall of socket 5. The material 38 also enters into the grooves 27 and assists in fixedly anchoring staff 1 and element 19 together.

When the handle is unlatched from the staff, 50 the parts will appear as shown in Figure 2. It will be assumed that the handle and staff are to be connected together. The element 18 is inserted into element 19 in a manner so pin or stud 22 will enter stretch 32 of slot 31 and the free end of element 18 bear against spring 37, the latter being in an expanded condition. At this point, when element 18 is moved further into element 19, the spring 37 is compressed and the pin 20 will coat with the walls of stretch 32 to cause 55 the handle to automatically rotate and bodily carry pin 20 in a direction to enter leg 34 and pass through the latter to the open end of leg 35. At this point, the handle is relieved of pressure, then spring 37 will automatically expand, force pin 20 into leg 35 thereby completing the latching operation and will maintain the pin 20 in latching 60 position. The latching structure will then appear as in Figure 1 and function to latch the handle and staff together. When unlatching, an inward movement is applied to the handle until pin 20 is arrested by leg 34; then a slight counter-clockwise turn is given the handle; at this point spring 37 will then act to force the element 18 from element 19 thereby detaching the handle 65 from the staff. When the handle and staff are

connected together the outer end portion of element 19 and member 9 extend into the pocket 24.

What I claim is:—

1. A latching structure for detachably connecting the handle and staff of an umbrella together, 80 a latching element adapted to be anchored to and extend from said handle and provided with a laterally extending pin adjacent the latter, a tubular combined guide and keeper element for the reception of the latching element and adapted to be anchored to and extend from said staff, said combined guide and keeper element being provided with a slot having a stretch of spiral form opening at one end at the free end of the keeper element and an L-shaped stretch formed of a horizontal leg and a longitudinal leg disposed lengthwise of the keeper element, opposing a part of the spiral stretch and having a closed end and an open end, said spiral stretch opening at one end into one end of the horizontal stretch, said horizontal leg opening at its other end into the open end of the longitudinal leg, said stretch and horizontal leg for the passage of said pin to the said other leg, said stretch coating with the pin for rotating the latching element during the 95 travel of the pin to the longitudinal leg, and an expelling means arranged within the combined guide and keeper element and bearing against the latching element for holding said pin within and against the closed end of the longitudinal leg. 100

2. The combination with a handle having a shank portion formed with a socket opening at one end thereof, and a staff provided with a socket opening at one end thereof, of a latching element anchored in the socket of and extended from said handle, said element being formed on its extended portion with a laterally disposed pin, a tubular keeper element anchored in the socket of, extended from the staff and for the reception of the extended portion of said latching 110 element, said keeper element being formed with a slot opening at one end of the edge of the extended portion thereof and provided with a spiral stretch and an L-shaped stretch, the latter consisting of a horizontal leg and a leg at right angles to the latter, opposing in spaced relation a part of the spiral stretch and having one end thereof closed, said horizontal leg opening into the other end of said spiral stretch and at its other end into the other end of the said other leg, said pin and slot coating for latching said 115 elements together when the latching element is extended into the keeper element, and a resilient expelling means for the handle, mounted in the keeper element for bearing against the latching element to maintain said pin in said L-shaped stretch to releasably hold said elements in latching engagement. 120

3. The combination with a handle having a shank portion formed with a socket opening at one end thereof, and a staff provided with a socket opening at one end thereof, of a latching element anchored in the socket of and extended from said handle, said element being formed on its extended portion with a laterally disposed pin, a tubular keeper element anchored in the socket of, extended from the staff and for the reception of the extended portion of said latching element, 135 said keeper element provided with means coating with said pin for latching said elements together and for rotating the handle in a direction to be latched to the staff, and a resilient expelling structure for the handle mounted in the keeper element for bearing against the latching element to main- 140

tain said pin in said means to releasably hold said elements in latching engagement.

4. The combination with a handle having a shank portion formed with a socket opening at one end thereof, and a staff provided with a socket opening at one end thereof, of a latching element anchored in the socket of and extended from said handle, said element being formed on its extended portion with a laterally disposed pin, a tubular keeper element anchored in the socket of, extended from the staff and for the reception of the extended portion of said latching element, said keeper element provided with means coact-

ing with said pin for latching said elements together and for rotating the handle in a direction to be latched to the staff, a resilient expelling structure for the handle mounted in the keeper element for bearing against the latching element to maintain said pin in said means to releasably hold said elements in latching engagement, and said staff being provided at the mouth of its socket with an axially apertured reinforcing means therefor for the passage of the latching element.
